UNITED STATES PATENT OFFICE.

EUGENE EDWIN MITCHELL, OF LAKE CITY, MINNESOTA.

DESIGN FOR A SCISSORS-BLADE.

SPECIFICATION forming part of Design No. 32,582, dated April 24, 1900.

Application filed March 6, 1900. Serial No. 7,599. Term of patent 14 years.

To all whom it may concern:

Be it known that I, EUGENE EDWIN MITCHELL, a citizen of the United States, residing at Lake City, in the county of Wabasha and 5 State of Minnesota, have invented and produced a new and original Design for a Scissors-Blade, of which the following is a specification.

My invention relates to a new and original 10 design for a scissors-blade and is shown in the accompanying drawings, in which—

Figure 1 is an elevation, and Fig. 2 a section on the line 2 2 of Fig. 1.

The leading feature of my design resides in 15 a scissors-blade formed with a projection from its back edge near its point, the front and rear edges of the projection being beveled to a sharp line.

In the drawings, the reference-numeral 1

indicates a scissors-blade formed near its point 2 with a projection 3, extending from its back edge 4. The front and rear edges of this projection are beveled to sharp lines 5 and 6. The beveling of the edges of the projection is more clearly shown in the sectional view, Fig. 2.

Having thus described my invention, what I claim is—

The design for a scissors-blade herein shown and described.

In testimony whereof I have hereunto set my hand in presence of two subscribing witnesses.

EUGENE EDWIN MITCHELL.
